UNITED STATES PATENT OFFICE

WALLACE W. BUGH, OF NORTH TONAWANDA, NEW YORK

VEHICULAR TRAFFIC-SIGNAL SWITCH

Original application filed April 5, 1927, Serial No. 181,225. Divided and this application filed May 5, 1928.
Serial No. 275,351.

This application is a division of that for which, on the 5th day of April, 1927, I made application for patent in the United States, Serial No. 181,225, and relates to a novel and peculiar switch mechanism and a unique re-setting mechanism, the switch mechanism embodying a few number of parts and utilizing certain switch elements as means for holding the pivoted switch member in normal position, thereby obviating the necessity for providing additional springs and stops for such purpose.

While the drawing illustrates a preferred embodiment of the invention, it is to be understood that in adapting the means to meet specific needs and requirements the design may be varied and such other changes in the minor details of construction may be resorted to within the scope of the invention as 20 claimed, without departing from the spirit thereof.

For a full understanding of the invention and the merits thereof, reference is to be had to the following description and the 25 drawing hereto attached, in which,

Figure 1 is a horizontal sectional view of a signal light switch mechanism embodying the invention, showing it applied to a steering post which is illustrated in section.

Figure 2 is a sectional view of the switch on the line 2—2 of Figure 1.

Figure 3 is a sectional view on the line 3—3 of Figure 2.

Figure 4 is a sectional view on the line 35 4—4 of Figure 3.

Corresponding and like parts are referred to in the following description and designated in the several views of the drawing by like reference characters.

The numeral 1 designates the usual steering post of a motor vehicle and 3 a bracket mounted thereon and secured thereto by means of a shackle 4 which embraces the steering post and has its threaded ends 45 gaging terminal portions of a depending portion of the bracket, which as shown most clearly in Figure 1 of the drawings, is cut away to receive the steering post, the cut away portion being of V-outline to adapt the 50 bracket to different sizes of steering posts.

A box 5 is attached to the V-bracket 3 and provides a housing for the switch mechanism and may be of determinate construction. A shaft 6 extends through the box 5 and is mounted in the front and rear walls thereof, 55 and is electrically insulated therefrom in any preferred way. A handle 7 is fast to the rear end of the shaft and is conveniently positioned so as to be readily accessible when it is required to operate the signal light.

A plate 8 within the box or housing 5 is fast to the shaft 6 and carries two pins 9 and 10 which have a parallel relation and project from opposite sides of the plate. These pins constitute bridge pieces whereby 65 to electrically connect the terminals of the respective light circuits.

V-shaped contact members 11 and 12 are located within the box or housing 5 and are adapted to cooperate with the pins 9 and 10. 70 The diverging elements 13 comprising the member 11 constitute spring terminals, the ends of which are depressed, as indicated at 13^a and project, as indicated at 13^b, to form stops. The diverging elements 12^a of the member 12 constitute spring terminals, the 75 end portions of which are similarly depressed and extended in substantially the same manner as the end portions of the spring terminals 13. Other spring terminals 14 are provided to cooperate with the spring terminals 12^a and are reversely disposed, their end portions being depressed, as indicated at 14^a and extended to provide stops 14^b. The parts are arranged so that normally the pins 9 and 10 80 engage the extended ends 13^b and 14^b of the respective spring terminals 13 and 14 without touching the spring terminals 12^a, hence the light circuits are normally open. When the shaft 6 is turned in a clock-wise direction the pin 10 is depressed and engages the spring terminal 12^a, thereby closing the light circuits. The pin 10 snaps into the depressions of the several spring terminals 13, 14 and 12^a and is retained in such position until the switch 85 is tripped and restored to normal position when the steering wheel is set to direct the vehicle straight ahead after the indicated turn to the right has been made.

When the shaft 6 is turned in a counter- 100

clockwise direction the pin 9 is depressed, and makes contact with the elements 12^a, thereby connecting the left hand light circuits, and indicating the intention of the 5 driver to make a left turn. The pin 9 snaps into the depressions of the spring terminals 13, 14 and 12^a and is retained in such position until the switch is tripped by turning the steering wheel 2 to direct the vehicle straight 10 ahead after the left turn has been made. When the switch is in neutral position, the pins 9 and 10 are engaged by the terminal extensions of the elements 13 and 14, and clear the spring terminals 12^a, hence the light circuits 15 are opened. It will thus be understood that the extensions of the spring terminals 13 and 14 constitute stops and guides and obviate the necessity for providing extraneous stop and guide means. 20 A plate 20 is fast to the forward end of the shaft 6, beyond the box or housing 5. The plate 20 has an extension 21 which forms stop shoulders to limit the movement of dogs 22 which are pivoted intermediate their ends to 25 the plate 20. A contractile spring 23 connects the lower ends of the dogs 22 and holds them in contact with the stop shoulders provided by the extension 21. The upper ends of the dogs 22 are beveled, as indicated at 24. 30 Normally the dogs 22 occupy a vertical position, as indicated by full lines in Figure 4, and assume an inclined position accordingly as the shaft 6 is turned to the right or to the left. A pair of pins 25 project from the 35 hub of the steering wheel, and are adapted to cooperate with each of the dogs 22. Assuming that the handle 7 is turned to the right, the pin 10 is depressed and bridges the spring terminals at the right and closes the light 40 circuits in which said terminals are included. This causes the plate 20 and dogs 22 to assume the position indicated by the dotted lines in Figure 4. The signal circuits are closed in advance of making the turn, thereby giving 45 ample warning of the intention of the driver.

When the vehicle is turning right around a corner, one of the pins 25 engages the upper projecting end of the left hand dog 22 which pivots to admit of the pin 25 clearing the 50 same. After the turn has been made and the vehicle is directed straight ahead the pin 25 previously clearing the dog 22 engages and actuates said dog, thereby tripping the switch and automatically breaking the light circuits 55 previously closed and restoring the switch to normal position, as will be readily understood.

A pair of contacts 26 is located at each side of the box or housing 5 and the contacts of each pair are adapted to be bridged by 60 the respective circuit closing pins 9 and 10. Corresponding contacts of each pair are electrically connected, as indicated most clearly in Figure 2. When the set or group of contacts at the right are closed by the pin 10, 65 the pair of contacts 26 at the left are closed

by the pin 9 and vice versa. These pairs of contacts 26 are included in a circuit which contains a device 27 for interrupting the circuit whereby to produce a flash signal instead of a continuously illuminated signal, 70 thereby being more attractive. Binding posts 28 have the pairs of contacts 26 electrically connected thereto, and these binding posts are adapted to have the lead wires from the battery or source of supply connected thereto. Binding posts 29 applied to the bottom of the box or housing 5 have the respective contacts 11, 12 and 14 connected thereto and the lead wires from the battery in connection therewith. 75

Having thus described the invention, I claim:

1. In combination with the switch mechanism of directional signal circuits for a vehicle, including a pivoted switch member and oppositely disposed circuit closing contacts, a resetting mechanism for restoring the switch to normal position after being actuated, the same comprising a plate connected to the pivoted switch member, dogs pivoted to said plate and yieldably connected to each other and stops carried by the steering wheel, and adapted to engage either one of the dogs to actuate the resetting mechanism upon returning the steering wheel to 95 a straight ahead position.

2. A direction signal for vehicles, the same comprising a pivoted switch member, oppositely disposed contacts, a circuit closing element carried by the pivoted switch member, a plate fixed to the pivoted switch member to turn therewith, said plate having stop shoulders, a pair of dogs pivoted to said plate and adapted to normally engage the shoulders to limit the pivotal movement thereof in one direction, and stop pins carried by the steering wheel and adapted to selectively engage the dogs to restore the switch to normal position when the steering wheel is turned to a straight-ahead position. 105

In testimony whereof I affix my signature.
WALLACE W. BUGH. [L. s.]
